CARD STRUCTURE

Stanley B. Freiberg, Cincinnati, Ohio, assignor
to The International Visible Systems Corporation,
Cincinnati, Ohio, a Corporation of Ohio

Application November 15, 1930
Serial No. 495,861

21 Claims. (Cl. 129—16.7)

This invention relates to improvements in an index card structure.

An object of the invention is to provide an improved index card and associated indicator means 5 of simple and inexpensive construction.

Another object is to provide a card structure of the above character in which the movable parts are protected from breakage and mutilation without the use of complicated and expensive attachments.

Another object is to provide a device of the above character wherein the parts are so arranged as to effectively preclude accidental dis- 10 arrangement thereof resulting in inaccuracies in the record desired to be kept.

These and other objects are attained by the means described herein and disclosed in the accompanying drawing, in which:

Fig. 1 is a plan view of the front of the im- 20 proved card.

Fig. 2 is a view similar to Fig. 1, the front cover or record portion thereof being removed.

Fig. 3 is an enlarged cross-sectional view taken on line 3—3 of Fig. 2.

The improved card comprises a rectangular sheet, suitably slotted and perforated, and folded twice upon itself to provide the front record portion 4, an inner depending short flap 5, and a back 6. The members 4, 5 and 6 each are perforated as at 7, through which perforations are threaded, in a certain manner to be described, a spring-metal card-mounting rod or bar 8 the opposite ends 9 of which extend beyond the side edges of the card structure. The mounting bar 25 or rod preferably, though not necessarily, is of flat material, and its ends are adapted to be received in suitable aligned openings in the opposite sides of an index card holder, in a manner well known.

Between the front record portion 4 and the back 6 is disposed for sliding movement a slide or indicator member 10 which has but one accessible part, a tab 11. The tab preferably is integral with the slide and it extends upwardly 40 through a longitudinal slit 12 in the record portion 4. The slit extends longitudinally of, and preferably in parallelism with, the top edge 13 of the record portion 4. The tab is of such height that it nearly reaches the upper edge 13.

It is to be noted that the bar 8 is so threaded through the perforations 7 of each portion 4, 5 and 6, as to cover the top edge 14 of the tab thereby precluding any tendency of the tab to turn forwardly and become mutilated when in use. 55 The exposed portion of the tab is large enough

to permit use of a lead pencil eraser in moving the tab from one side of the card toward the other side thereof.

The tab being attached to or integral with the slide 10, the slide will move bodily with the tab. 60

The slide is guided in its sidewise movement by means of a pair of opposed tongues 15 formed in the slide by slitting the slide as at 16 in the direction of its movement and then forming the parallel transverse slits 17 and 18 at the ends of slit 16. At the four ends of slits 17 and 18 are cut-out portions 19 which preclude binding at the ends of the slits and thereby facilitate sliding movement of the slide. 65

The tongues 15 are adapted to be placed behind a guide 20 formed by slitting the flap 5 longitudinally thereof at 23, at a distance from its lower edge 21 substantially equal to the length of slits 17 and 18. The tongues may be disposed behind the guide 20 as indicated in Figs. 2 and 3, and it should readily be apparent that the slide connection thereby provided will not permit of cocking or wobbling of the slide. It is to be noted particularly that the short parallel edges 22 adjacent the cut-out portions 19 ride upon the edges 21 and 23 of the guide 20 in nearly the same plane, wherefore the ends of slits 17 and 18 are not subjected to cutting action of the edges 21 and 23 when the parts are relatively moved. The fact that the construction permits the use of a large slide, of approximately one-third or one-half the area of the card, lends great stability to the slide and assists in decreasing the liability of the slide to wobble. 70 75 80 85 90

Extending upwardly from the slide 10, on each side of the tab, are the projections 24 which enter a slit 25 located adjacent to the bases of the tab and projections. This slit is parallel to slit 23 and the top edge of the card. The extensions 24 fit in the fold between the members 5 and 6 and are subjected to the yielding force of the bar 8 when threaded through the openings 7. These extensions and tab 11, in the before-mentioned cooperative relationship with bar 8, serve to preclude accidental displacement of the slide when the index card is in use. 95 100

Extending from the bottom edge of the slide is a marker portion 26, having an indicator 27 which may be a mark printed, painted or otherwise applied to the marker portion. The marker portion 26 depends to a point closely adjacent the line of juncture of members 4 and 6. The indicator is rendered visible through each of a series of perforations or windows 28 in the record or cover portion 4, by moving the slide 10. The 105 110

perforations 28 may be of any desired shape or spacing. In the drawing, each perforation or window is of the shape of a parallelogram, and each is disposed obliquely to the bottom edge of 5 the card. One end of each perforation is located directly above and in spaced relation with one end of the next succeeding perforation, and all are parallel to one another. By this means of locating the perforations, they are sufficiently 10 separated from one another to preclude materially weakening the sheet in that region, and in addition, a maximum of indicating space is obtainable in the least amount of space. It is advantageous in most instances to overlap adjacent 15 index cards as much as possible so as to conserve space, and for that reason the openings 28 are arranged as shown and described. This is thereby accomplished without unduly weakening the card.

20 The openings may have any desired relationship with the marker or indicator, for example, each opening may be four times the width of the indicator 27, and there may be thirteen of them, each representing four weeks of the year. When 25 the indicator is placed in the last quarter of one opening 28, there is indicated the last week in a given period. The number of openings and the width of the indicator mark may be varied, however, to adapt the device for various uses. The 30 material of which the device is constructed may vary also, and an advantage of the structure is that both the card and slide may be made of ordinary paper, and not necessarily of stiff material. In fact, the devices of this invention now 35 in use are of ordinary writing paper, and they are very inexpensively manufactured. The fact that the construction permits the use of a large slide of comparatively light weight material and of approximately one-third or one-half the area 40 of the area of the card, lends great stability to the slide and assists in decreasing the liability of the slide to wobble.

What is claimed is:

1. In a device of the class described the combination of a card body, a card-mounting member extending along a face of the card body in close proximity therewith, a slide associated with the card body, and a tab on the slide disposed for sliding movement between the mounting member and the adjacent face of the card.
2. In a device of the class described the combination of a card body, a card-mounting member extending along a face of the card body in close proximity therewith, a slide associated with the card body, and a tab on the slide disposed for sliding movement between the mounting member and the adjacent face of the card, the slide having an extension disposed behind the card-mounting means.
3. In a device of the class described the combination of a card body, a card-mounting member extending along a face of the card body in close proximity therewith, a slide associated with the card body, cooperative means on the card body and slide for guiding the slide, and a tab on the slide disposed for sliding movement between the mounting member and the adjacent face of the card.
4. In a device of the class described the combination of a card body, a card-mounting member extending along a face of the card body in close proximity therewith, a slide associated with the card body partially disposed beneath a face of 75 the card body, and a tab on the slide disposed for

sliding movement between the mounting member and the adjacent face of the card.

5. An index card assembly comprising a card body, a movable slide carried by the card body, a guide means on the slide, and cooperative guide means on the card formed by a terminal edge of the card body and a single slit in the material of the card body, the edge and the slit being spaced from one another and engaged by the slide.

6. An index card assembly comprising a card body, a movable slide carried by the card body, and cooperative guide means on the slide and card body for guiding the slide, and a cover for the slide and the cooperative guide means.

7. An index card assembly comprising a card body, a movable slide carried by the card body, and cooperative guide means on the slide and card body for guiding the slide, and a cover for the slide and the cooperative guide means, the cover being an integral folded-over part of the card body.

8. An index card comprising a body made up of a back, a flap folded upon the back, and a front cover folded upon the flap and the back, the flap being slitted to provide a guide, and a slide mounted upon the guide and covered substantially by the front cover.

9. An index card comprising a body made up of a back, a flap folded upon the back, and a slotted front cover folded upon the flap and the back, the flap being slitted to provide a guide, a slide mounted upon the guide, a tab on the slide extending through the slit in the front cover, the front cover serving to cover the slide exclusive of its tab.

10. An index card comprising a body made up of a back, a flap folded upon the back, and a slotted front cover folded upon the flap and the back, the flap being slitted to provide a guide, a slide mounted upon the guide, a tab on the slide extending through the slit in the front cover, the front cover serving to cover the slide exclusive of its tab, and a card-mounting member covering a portion of the tab for protection thereof.

11. An index card comprising a body made up of a back, a flap folded upon the back, and a slotted and perforated front cover folded upon the flap and the back, the flap being slitted to provide a guide, a slide mounted upon the guide, a tab on the slide extending through the slit in the front cover, said front cover serving to cover the slide exclusive of its tab, and an indicator on the slide observable through the perforations in the front cover.

12. An index card comprising a body made up of a back, a flap folded upon the back, and a slotted front cover folded upon the flap and the back, said cover being provided with windows the flap being slitted to provide a guide, a slide mounted upon the guide, a tab on the slide extending through the slit in the front cover, the front cover serving to cover the slide exclusive of its tab, an indicator on the slide observable through the above mentioned windows in the cover, said windows being disposed obliquely to an edge of the front cover.

13. A slide for index card assemblies comprising a body, an actuating means on the body, whereby the slide may be grasped and moved, the body having a pair of spaced slits connected by a third slit.

14. A slide for index card assemblies comprising a body of flexible material, an actuating means on the body, whereby the slide may be grasped

and moved, the body having a pair of spaced slits connected by a third slit, and cut-out portions at the opposite ends of each of the pair of spaced slits to provide sliding edges.

indicating means having an end located directly above an end of the succeeding indicating means and so related that any line drawn perpendicularly to the row of indicating means will pass through but one of them.

80

5 15. An index card assembly made entirely of thin paper comprising a card body having perforations therein, a movable slide carried by the card body and comprising a sheet of approximately one-half the size of the card body, and cooperative guide means on the slide and card body and disposed adjacent to one edge of the card body, for guiding the slide, and an indicating marking on the slide said marking being adjacent to the opposite edge of the card body and observable through the above-mentioned perforations in the card body.

19. An index card provided with oblong windows which are disposed in substantial parallelism obliquely to an edge of the card.

85

10 10. An index card provided with oblong windows which are disposed in a row and in substantial parallelism, obliquely to an edge of the card, one end of each window being located directly above and in spaced relation with an end of the next succeeding window.

20. An index card provided with oblong windows which are disposed in a row and in substantial parallelism, obliquely to an edge of the card, one end of each window being located directly above and in spaced relation with an end of the next succeeding window.

90

15 15. An index card having indexing means constituted partly of oblong windows disposed obliquely to an edge of the card.

21. In combination an index card provided with oblong windows which are disposed in a row and in substantial parallelism, obliquely to an edge of the card, one end of each window being located above and in spaced relation with an end of the succeeding window and a movable marker disposed behind the face of the windowed portion of the card and observable through the obliquely disposed oblong windows.

95

20 17. An index card having oblong windows disposed in substantial parallelism obliquely to and closely adjacent the lower edge of the card.

25 18. An index card having indicating window means disposed in a row and in substantial parallelism obliquely to an edge of the card, each of said

STANLEY B. FREIBERG. 100

10 10. An index card having indicating window means disposed in a row and in substantial parallelism obliquely to an edge of the card, each of said

105

15 15. An index card having indicating window means disposed in a row and in substantial parallelism obliquely to an edge of the card, each of said

110

20 10. An index card having indicating window means disposed in a row and in substantial parallelism obliquely to an edge of the card, each of said

115

25 15. An index card having indicating window means disposed in a row and in substantial parallelism obliquely to an edge of the card, each of said

120

10 10. An index card having indicating window means disposed in a row and in substantial parallelism obliquely to an edge of the card, each of said

125

15 15. An index card having indicating window means disposed in a row and in substantial parallelism obliquely to an edge of the card, each of said

130

20 10. An index card having indicating window means disposed in a row and in substantial parallelism obliquely to an edge of the card, each of said

135

25 15. An index card having indicating window means disposed in a row and in substantial parallelism obliquely to an edge of the card, each of said

140

10 10. An index card having indicating window means disposed in a row and in substantial parallelism obliquely to an edge of the card, each of said

145

15 15. An index card having indicating window means disposed in a row and in substantial parallelism obliquely to an edge of the card, each of said

150

20 10. An index card having indicating window means disposed in a row and in substantial parallelism obliquely to an edge of the card, each of said
